UNITED STATES PATENT OFFICE.

THOMAS R. COOK, OF PITTSBURGH, PENNSYLVANIA.

GRATE.

1,108,887.

Specification of Letters Patent.

Patented Sept. 1, 1914.

Application filed April 10, 1912. Serial No. 639,798.

To all whom it may concern:

Be it known that I, THOMAS R. COOK, a citizen of the United States, residing at Pittsburgh, in the county of Allegheny and State of Pennsylvania, am the inventor of certain new and useful Improvements in Grates, of which the following is a specification.

The invention relates to grates, and in the particular embodiment of the invention illustrated, to grates for underfeed stoker furnaces, it being understood, however that the invention is of general application, and useful in relations other than the one illustrated. The invention has for its primary objects; the provision of an improved type of grate wherein the shaking grates act as drop grates thus obviating the necessity of providing special drop grates; the provision of a structure of the character specified in which an adequate space is provided for dumping the contents of the furnace; the provision of a structure of the character specified wherein the opposing grate bars are connected so that they counterbalance each other and may be easily moved in unison in the shaking operation. Certain embodiments of the invention are illustrated in the accompanying drawings, wherein—

Figure 1 is a section through a locomotive firebox and shows the improved grate structure in plan view; Fig. 2 is a transverse section on the line II—II of Fig. 1; Fig. 3 is an end elevation of the connecting means employed between the two rotatable grate bars, and Fig. 4 is a transverse section through a modification.

The grate construction is particularly adapted for use upon underfeed stokers, and is illustrated as so applied in Figs. 1 and 2 wherein 1 is the water leg of a locomotive firebox, 2 and 3 are underfeed troughs through which the fuel is fed by means of auxiliary plungers 4, 5, and 6, and by means of main plungers at the ends of the troughs (not shown). In the particular embodiment of the invention as illustrated in Figs. 1 and 2, four grate bars 8, 9, 10, and 11 are employed, which grate bars extend from one end of the firebox to the other and are supported for rotation at their ends as indicated in Fig. 1. Intermediate the ends of the bars 8 and 11 are what may be termed bearing plates 12 and 13, which bearing plates serve to give the bars 8 and 11 the necessary supports intermediate their ends.

Similarly intermediate the ends of the bars 9 and 10 are the bearing plates 14 and 15, such plates being supported upon the edges of the trough. Mounted removably upon these bars 8, 9, 10, and 11 are the cast sections provided with the grate fingers, the bars being square in cross section so that the sections are nonrotatable with respect thereto. The upper side edges of the troughs 2 and 3 are preferably in the form of the cast metal bars 16, 17, 18, and 19, which bars are provided with the downwardly and outwardly projecting link fingers 20. Similarly the cast side bars 21 and 22 are provided with upwardly and inwardly inclined grate fingers 23. The grate sections on the bars 8 and 11 coöperating with the fingers 20 and 23 constitute the side grates and are operated to shake the grate by means of a suitable tool or wrench which engages the squared outer ends 24 of the bars.

The grate sections carried by the rotatable bars 9 and 10 are each provided with two sets of fingers, the first set comprising the relatively short upwardly and outwardly projecting fingers 25, and the other set comprising the inwardly and downwardly projecting fingers 26, which latter fingers extend laterally at their lower ends. The outer ends of the bars 9 and 10 are provided with the rock arms 27 and 28, and these rock arms are releasably connected by means of the connecting rod 29, such rod having its left hand end forked as indicated in Fig. 3 and being secured at such end to the arm 27 by means of the removable bolt 30. It will be seen that both of the bars 9 and 10 are rocked when one of the rocker arms 27 or 28 is moved, so that any desired amount of shaking movement may be applied to the fingers carried by the bars 9 and 10 by oscillating the rocker arms 27 and 28 either directly or by means of a suitable tool or handle. The amount of this rocking movement is limited by the engagement of the edge of the rocker arm 27 with the end 31 of the fork. When it is desired to convert this rocking grate into a drop grate, the connecting rod 29 is disengaged at its left hand end as indicated in Fig. 3, thus permitting the grate fingers 26 to assume the position indicated in dotted lines in Fig. 2. A comparatively large open space extending throughout the entire length of the furnace is thus secured. The connecting rod 29

serves not only to secure the counterbalancing of the opposing grates on the bars 9 and 10, but also serves to secure the simultaneous rocking of the two sets of fingers by the 5 operation of one of the rocker arms 27 or 28. As indicated most clearly in Fig. 3, the fingers 25 are made of very considerable depth and rounded or curved upon their outer faces, such arrangement being desirable in that when the device is used as a drop grate the fingers 25 still intermesh with the fingers 20, and the crevice or opening which would otherwise occur between the two sets of fingers is avoided. As a result 10 there is no difficulty in moving the grate bars 9 and 10 to their operative position from the drop position, as would be the case if a space were formed between the fingers 25 and 20 for the reception of clinker and 15 other material tending to prevent the return movement of the bars.

In dropping the grate, one of the rock arms 27 or 28 is locked or held in position by any desired means while the other one 25 is moved slightly to permit the removal of the bolt 30 after which each bar is permitted to move to drop position. The reverse operation occurs when it is desired to bring the parts to operative position again as indicated in Figs. 2 and 3.

A slightly different embodiment of the invention is illustrated in Fig. 4 wherein a third rotatable bar 32 is provided intermediate the rotatable bars 33 and 34. This 35 bar 32 carries the grate sections 35, and the dumping operation is secured by moving the bars 32, 33, and 34 so that their fingers occupy the vertical position as indicated in dotted lines in the figure. This construction 40 may well be utilized in constructions wherein the distance between the troughs is so great that the construction of Fig. 1 is impracticable. It will be understood that various other modifications of the structure 45 might be made without departing from the spirit of the invention, the apparatus as therein shown being merely illustrative of the invention whose scope is limited only by the definition thereof as set forth in the 50 claims.

Having thus described my invention and illustrated its use, what I claim as new and desire to secure by Letters Patent, is the following:

55 1. In combination in a furnace having opposing sets of fixed grate fingers inclined downwardly and extending longitudinally of the furnace, and having means for supplying fuel upon the said sets of grate fingers, of a pair of rotatable grate bars lying 60 between and below the said sets of fingers and each having a set of upwardly extending fingers coöperating with the said downwardly inclined fixed fingers and having another set of fingers projecting down-

wardly to form a basket grate, and releasable means for limiting the rocking movement of the grate bars adapted when released to permit the downwardly projecting fingers of the said bars to swing away from 70 each other to provide a dumping space.

2. In combination in a furnace having opposing sets of fixed grate fingers inclined downwardly and extending longitudinally of the furnace, and having means for supplying fuel upon the said sets of grate fingers, of a pair of rotatable grate bars lying between and below the said sets of fingers and each having a set of upwardly extending fingers coöperating with the said downwardly inclined fixed fingers and having another set of fingers projecting downwardly to form a basket grate, and releasable means for limiting the rocking movement of the 75 grate bars and when released to permit sets of fingers on the said bars to swing to substantially vertical position to provide a dumping space.

3. In combination in a furnace having opposing sets of fixed grate fingers inclined downwardly and extending longitudinally of the furnace, and having means for supplying fuel upon the said sets of grate fingers, of a pair of rotatable grate bars lying 80 between and below the said sets of fingers and each having a set of upwardly extending fingers coöperating with the said downwardly inclined fixed fingers and having another set of fingers projecting downwardly to form a basket grate, and releasable means for limiting the rocking movement of the 85 grate bars and when released to permit sets of fingers on the said bars to swing to substantially vertical position to provide a dumping space.

4. In combination in a furnace having

opposing sets of fixed grate fingers inclined downwardly and extending longitudinally of the furnace, and having means for supplying fuel upon the said sets of grate fingers, of a pair of rotatable grate bars lying 90 between and below the said sets of fingers and each having a set of upwardly extending fingers coöperating with the said downwardly inclined fixed fingers and having another set of fingers projecting downwardly to form a basket grate, and releasable means for limiting the rocking movement of the 95 grate bars and when released to permit sets of fingers on the said bars to swing to substantially vertical position to provide a dumping space.

5. In combination in a furnace having opposing sets of fixed grate fingers inclined downwardly and extending longitudinally of the furnace, and having means for supplying fuel upon the said sets of grate fingers, of a pair of rotatable grate bars lying 100 between and below the said sets of fingers and each having a set of upwardly extending fingers coöperating with the said downwardly inclined fixed fingers and having another set of fingers projecting downwardly to form a basket grate, and releasable means for limiting the rocking movement of the 105 grate bars and when released to permit sets of fingers on the said bars to swing to substantially vertical position to provide a dumping space.

6. In combination in a furnace having opposing sets of fixed grate fingers inclined downwardly and extending longitudinally of the furnace, and having means for supplying fuel upon the said sets of grate fingers, of a pair of rotatable grate bars lying 110 between and below the said sets of fingers and each having a set of upwardly extending fingers coöperating with the said downwardly inclined fixed fingers and having another set of fingers projecting downwardly to form a basket grate, and releasable means for limiting the rocking movement of the 115 grate bars and when released to permit sets of fingers on the said bars to swing to substantially vertical position to provide a dumping space.

7. In combination in a furnace having opposing sets of fixed grate fingers inclined downwardly and extending longitudinally of the furnace, and having means for supplying fuel upon the said sets of grate fingers, of a pair of rotatable grate bars lying 120 between and below the said sets of fingers and each having a set of upwardly extending fingers coöperating with the said downwardly inclined fixed fingers and having another set of fingers projecting downwardly to form a basket grate, and releasable means for limiting the rocking movement of the 125 grate bars and when released to permit sets of fingers on the said bars to swing to substantially vertical position to provide a dumping space.

8. In combination in a furnace having opposing sets of fixed grate fingers inclined downwardly and extending longitudinally of the furnace, and having means for supplying fuel upon the said sets of grate fingers, of a pair of rotatable grate bars lying 130 between and below the said sets of fingers and each having a set of upwardly extending fingers coöperating with the said downwardly inclined fixed fingers and having another set of fingers projecting downwardly to form a basket grate, and releasable means for limiting the rocking movement of the grate bars and when released to permit sets of fingers on the said bars to swing to substantially vertical position to provide a dumping space.

of the furnace, and having means for supplying fuel upon the said sets of grate fingers, of a pair of rotatable grate bars lying between and below the said sets of fingers 5 and each having a set of upwardly extending fingers coöperating with the said downwardly inclined fixed fingers and having another set of fingers projecting downwardly and then substantially horizontally 10 to form a basket grate with the upwardly extending sets of fingers on the said bars of less length than the other sets of fingers

carried thereby, and releasable means for the bars adapted when released to permit the downwardly extending fingers of the 15 said bars to swing away from each other to provide a dumping space between the bars.

In testimony whereof I have hereunto signed my name in the presence of the two subscribed witnesses.

THOMAS R. COOK.
